UNITED STATES PATENT OFFICE.

THOMAS ATKINSON AND HORACE CARDWELL DAY, OF HEYWOOD, ENGLAND.

AUTOMATIC METAL-TYPE-DISTRIBUTING MACHINE.

Application filed August 31, 1922. Serial No. 585,887.

To all whom it may concern:

Be it known that we, THOMAS ATKINSON and HORACE CARDWELL DAY, subjects of the King of Great Britain and Ireland, residing at Glenthorne, Rochdale Road, East, Heywood, in the county of Lancaster, England, have invented new and useful Improvements in an Automatic Metal-Type-Distributing Machine, of which the following is a specification:

The invention relates to an automatic metal type distributing machine, a sequence of operations being performed automatically in such machine. The column or page of type to be distributed is laid on a galley and pushed line after line into a channel, and as each line is pushed from the galley, the galley, or the type, is actuated to bring the next line of type to coincide with the channel. Each type character in the channel is carried individually by a separator device up to a selection channel along which it is traversed. This selection channel is formed by a fixed wall and another wall provided by a series of movable selector heads. The type characters are held suspended in the selection channel by means of a projection on a fixed wall of the channel and on the selector heads, fitting into corresponding recesses provided at the shoulder of the type. Each type character has also a special recess or combination of recesses formed in the front side which faces the selector heads which are provided with a projection or projections, each selector head having only projections to correspond with the recesses of its own individual type character. As the type character is traversed along the selection channel when it comes opposite to its own individual selector head the projections on the selector head coincide with the recesses in the type character and an electric circuit is designed to be completed by means of which mechanism is actuated to withdraw the selector head, and the type character being thus released falls out of the selection channel and is led away by suitable means to drop it into its correct compartment in the type case or into a container in proper position ready for removal to a type setting machine.

The invention is illustrated in the accompanying drawings, in which,

Fig. 1 is a front elevation of the machine, broken in length, a portion only of the selector heads being shown.

Figs. 2 and 3 show two views of the strikers which are carried by an endless chain, and are used to traverse the type characters along the selection channel. 60

Fig. 4 is a plan view of Fig. 1.

Figs. 5 and 6 are two views of a portion of an endless chain and a pusher device carried at intervals thereon and used to propel a line of type from off the galley into the type channel from which single type characters are removed to the selection channel. 65

Fig. 7 is an end view of part of the machine looking in the direction of the arrow Fig. 1, on a larger scale than Fig. 1, a portion thereof being shown in section on the line A—B Fig. 1. 70

Figs. 8 to 14 are detail parts drawn on a larger scale.

Figs. 15, 16 and 17 are views on a larger scale of one of the selector heads, and,

Fig. 18 shows the electrically actuated mechanism used for releasing a selected type character from the selection channel.

Fig. 19 shows how the slide of the separator device is actuated. 80

In a type distributing machine made in accordance with our invention the metal type characters *a* used therewith are made with a recess *a'* near the shoulder on the front and back sides, by means of which they can be supported in the machine, and also a recess *a''* or combination of such recesses in various positions down the front side for selection by the selector heads for distribution. A specimen of such type is shown in the enlarged view Fig. 10a.

The column or page of such type to be distributed into their proper places is laid on a galley with a sliding base *b* (Figs. 1 and 4) 95 and held against a fixed side *b'* by means of an adjustable side *b''* operated by screws *b'''* rotatable by means of hand wheels *b''''*. The galley base *b* is supported in slides and at intervals upon rollers *b''* and is actuated 100 by a screwed spindle *c* to bring the first line of type against the fixed side *b'* opposite to the type channel *c''*. An endless chain *c'''* suitably driven from the power shaft *c''* of the machine, and indicated by dotted lines 105 in Fig. 4 carries a number of pushers *d* formed with a T shaped head. A portion of the chain with one of the pushers *d* is shown in Figs. 5 and 6. The reduced neck of the T head occupies a slot *d'* in the fixed side *c'* 110 of the machine (shown in Fig. 1) and the head coming behind the first line of type;

pushes the type into the channel c^2 and then emerges out of the slot d' at d^2 which is shaped to permit this as shown in Fig. 1. The galley base b is then moved forward to bring the next line of type to coincide with the type channel c^2 . This might be effected by rotating the screwed spindle c by means of a band or chain c^5 through the medium of an electrically controlled clutch on the driving shaft c^4 by using the pusher d as a contact piece to momentarily complete a circuit as it emerges out of the slot d in any known or convenient manner. The means for actuating the galley may be varied. For instance the galley could be actuated by means of a spring or load, or the galley may be stationary and the column or page of type could be pushed forward by a spring device. As soon as the line of type moved into the type channel c^2 has been dealt with in manner to be described, another pusher on the chain c^3 is timed to come into contact with the next line and so on until the column or page of type on the galley is exhausted.

The type characters now occupying the channel c^2 are individually lifted by a separator device and are slid into a selection channel e , one wall e' of which is fixed and continuous, the other wall being formed by a series of selector heads f . The end of the channel c^2 is provided by a receiver f' which is H shape in cross section and is separately shown in Fig. 8. The lower slot of the receiver f' is provided with projections f^2 which engage the shoulder recesses a' of the type characters so as to support the type. The foremost type is pushed from the receiver into the separator which is reciprocated to elevate each type character singly to coincide with and ready to be moved into the selection channel e along which it is to be traversed. The separator device is illustrated on a larger scale in Figs. 9 and 10, and 11 to 14, Fig. 14 being a cross section on the line C—D Fig. 12. It consists of a plunger g having two recessed sides, the recesses being occupied by two fork members g', g' , slideable in the recesses. This fork is carried by a cross head g^2 connected by links g^3, g^3 , to a rocking lever g^4 which can oscillate on a pivot g^5 and which is actuated by a cam h on a driven countershaft h' acting on a roller h^2 on the end of the lever g^4 . The plunger g carries a bolt i passing loosely through the cross head g^2 , around which is a coiled spring i' compressed between the cross-head and a screwed nut i^2 on the bolt, which nut is normally below the plunger thus providing a spring connection between the crosshead g^2 and the plunger g and permitting to a certain extent independent movement of the cross head. The plunger g is formed with a slot i^3 at its upper end having projections i^4, i^4 corresponding with the recesses a' in

the shoulder of the type character a and the plunger is disposed alongside the receiver f' . The plunger is provided with a slide j of a thickness corresponding to the thinnest type character used, into which a type character is pushed, such slide being also slotted at j' to receive the type and having projections j^2, j^2 corresponding with the recesses a' of the type character. Normally and as shown in Figs. 9 and 10, the slot j' in the slide j does not quite coincide with the slot in the plunger g , which prevents the separator receiving more than one type character at a time. When the slide j has received the type character the separator is timed to move upwards through the action of the cam h on the countershaft h' . In case the type character should be thicker than the slide j the receiver f' is arranged, before every upward movement of the plunger g to be retracted against the action of springs k secured to trunnions k' on the receiver f' and to studs k^2 screwed into the frame of the machine. This withdrawal of the receiver f' is effected by the spring connection between the plunger g and the fork g' , the top of the fork g' coming into contact with cams m carried by the upper part of the plunger g , turning the cams on their pivots, the cams being disposed against the end of the receiver f' which is thus thrust away from the plunger to a small extent releasing the type character and leaving room for the type character to pass it. To effect this the spring i' is further compressed due to the movement of the cross head g^2 whilst the plunger g remains stationary. When the receiver has been retracted the temporary further compressed coiled spring i' returns to normal compression, and the plunger g is raised by the crosshead g^2 in conjunction with the coiled spring i' . At the same time a pivoted finger k^3 engaging at one end with the slide j (see Fig. 9) coming into engagement with an adjustable stop k^4 is actuated to raise the slide until the slot j' therein coincides with the slot i^3 in the plunger g . The type character in the separator is then slid out of the separator into the selection channel e by one of a series of strikers n carried by an endless chain n' driven from the main driving shaft of the machine as shown in dotted lines in Fig. 1. A portion of the chain n' carrying a striker n is shown in Figs. 2 and 3 and each type character is acted upon by a separate striker. When the type character has been slid out of the separator, the separator moves down again and another adjustable stop o acts upon the finger k^3 to return the slide j to its normal position and it receives another type character. Fig. 19 illustrates more clearly the means for actuating the slide. The stops k^4 and o are secured by screwed studs k^5 and o^4 respectively, in slots

in the frame of the machine and the distance between such stops can be adjusted by slackening the screwed studs k^5 o^4 and rotating in one direction or the other the right and left hand screwed spindle o^5 by means of the nut o^6 thereon. Figs. 15 to 18 indicate clearly the selector heads f , Fig. 18 also showing the selection channel with a type character therein. The type character a is held suspended between the fixed wall e' of the selection channel e and a selector head f . Each selector head f is provided with a projection o^8 to fit into one of the recesses a' in the shoulder of the type character a , the fixed wall e' having a similar projection to fit into the other recess a' . Each selector head is supported by a rail o^9 and is slidable in a shallow channel formed across the rail. Connected to each selector head is a rod or bar o^2 passing through a groove formed in a fixed rail o^3 and supported at the end in a grooved pulley p loose on a shaft p' . A coiled spring p^2 on the rod o^2 is disposed between the rail o^3 and an adjustable stop p^3 and on each rod o^2 is an adjustable stop p^4 . For each selector head there is provided a delayed action relay q and a pivoted armature q' with appreciable inertia and the selector head also carries a slidable spring controlled block r on the face of which are projections r' . For each type character there is a selector head in which the projection or projections r' of the slidable block correspond with the recess or recesses a^2 on the front side of the type character. The relay q is wired to a battery s or other source of electric current connected to the frame of the machine and to an insulated contact point r^2 carried by the slidable block r . This contact point is thrust away from the type character by the projections r' so long as they do not coincide with the recesses in the type character, but when the type character reaches its individual selector head the projection or projections on the slidable block enter the groove or grooves in the type character without any backward movement of the block r , thus the type character and contact point r^2 complete the electric circuit which energizes the relay, the pivoted armature being then attracted to the relay. On this movement of the armature it comes into contact with the adjustable stop p^4 . The rod o^2 is thus slid in its bearings compressing the spring p^2 and carrying the selector head therewith whereby the type character is released and falls down the funnel t into the flexible tube t' by means of which it is directed into its correct compartment in a type case. The released type may however be led away by any suitable means, such as by a directional raceway for packing into containers. The spring p^2 on the release of the type character returns the selector head to its normal

position ready to receive the next type character. The required number of selector heads, corresponding to the number of type characters used, may be arranged in a straight line, or to economize space they may be curved in a semi-circle or the like. Separate views on a larger scale of the selector head are shown in Figs. 15 to 17. Fig. 17 being a section of the slidable block on the line E—F, Fig. 15. To prevent jambing of the type characters against the slidable block the projections r' thereon are tapered off where the type character first enters the selector head as shown in Fig. 17.

We may use interchangeable separators to deal with type of various standard sizes and also to accommodate various standard sizes of type we may make the fixed wall of the selection channel adjustable towards and from the selector heads.

We do not confine ourselves to the exact construction as this may be varied whilst still preserving the gist of our invention.

We declare that what we claim is:

1. In an apparatus for distributing metal type, a galley to receive the page of type to be distributed, a sliding base for such galley, means to clamp the type upon such galley base, and means to actuate the galley base to bring the type a line at a time opposite to a type channel, a receiver at the end of such type channel, means to carry the type suspended in such receiver, means to feed the type a line at a time into such type channel and receiver substantially as described.

2. In apparatus for distributing metal type, a type channel to receive a line of type, and a receiver at the end of such channel formed with projections to carry suspended the type fed therein, and with means to enable such receiver to yield against the action of springs substantially as described.

3. In apparatus for distributing metal type the combination of the type receiver with a separator device consisting of a plunger having two recessed sides, a cross head having two forked members occupying and slidable within such recessed sides, a rocking lever, links connecting the cross head to the rocking lever, means to oscillate such rocking lever, a spring device connecting the plunger to the cross head, permitting movement of the cross head independent of the plunger, a through way slot formed in the plunger and having projections to receive the type, a slide carried by the plunger to receive the type and having projections to correspond with recesses in the type, means to prevent the slide receiving more than one type character at a time, means, in case the type character should be thicker than the slide, to retract the type receiver to allow the type character to pass it, means to actuate the slide into co-incidence with

- the slot in the plunger, and means to slide the type character out of the slide and separator device at the required time substantially as described.
5. In an apparatus for use in distributing metal type, a selection channel for the type consisting of a continuous fixed wall, and a wall formed from a series of selector heads, means to suspend the type characters 10 within such selection channel, means to continuously traverse the type characters along the selection channel and means to release the type character when it comes opposite to its individual selector head and to conduct it away substantially as described.
5. In an apparatus for use in distributing metal type a series of selector heads forming the movable wall of a selection channel, each selector head having a projection to fit into one of the recesses in the shoulder of a type character, means to support and guide such selector heads, a relay and pivoted armature for each selector head, a slidable spring controlled block for each 25 selector head with projections to correspond with recesses on the face of its individual type character, an insulated contact point carried by the slidable block, a source of electric current connected to the frame of the machine and to the relay and the insulated contact point of the slidable block, means whereby on a type character reaching a selector head in which the projections of the slidable block co-incide with the grooves 30 in the face of the type character, an elec- tric circuit is completed and the selector head is actuated to release the type character substantially as described.
6. In combination in apparatus for distributing metal type, type characters 40 formed with a recess near the shoulder on the front and back sides and a recess or recesses in the front side, a type channel and means to feed such type a line at a time into such channel, a type receiver at 45 the end of such type channel with means to hold the type characters suspended in such receiver, a separator device, a slide carried by such separator device with means to enable the slide to receive the type characters 50 singly, means carried by the separator device to actuate the receiver to enable type thicker than the slide to pass the receiver, means to elevate the separator device, a selection channel consisting of a fixed wall 55 and a wall formed from a series of selector heads, means to remove the type character from the separator device and enter it into the selection chamber and traverse it continuously along such channel, means to sus- 60 pend the type within the selection channel, and means to release each type character when it comes opposite to its appropriate selector head, and conduct it away, substantially as described. 65

In testimony whereof we have signed our names to this specification.

THOMAS ATKINSON.
HORACE CARDWELL DAY.
